UNITED STATES PATENT OFFICE.

WILLIAM K. KNUTSON, OF WICHITA FALLS, TEXAS, ASSIGNOR TO KNUTSON VACUUM REFRIGERATOR COMPANY, OF WICHITA FALLS, TEXAS, A COMMON LAW TRUST.

REFRIGERATOR.

1,412,687.

Specification of Letters Patent. Patented Apr. 11, 1922.

Application filed September 7, 1920. Serial No. 408,762.

To all whom it may concern:

Be it known that I, WILLIAM K. KNUTSON, a citizen of the United States, residing at Wichita Falls, in the county of Wichita, 5 State of Texas, have invented certain new and useful Improvements in Refrigerators; and I do hereby declare the following to be a full, clear, and exact description of the invention, such as will enable others skilled 10 in the art to which it appertains to make and use the same.

This invention is a refrigerator, and the broad object thereof is to construct the same with its walls and doors of wood packed 15 with comminuted material, separated by a vacuum chamber or jacket from an inner shell which surrounds the food space, the shell by preference being of reinforced concrete, whereby the food will never be contaminated by the outer wall nor the outer 20 wall ever receive dampness from the inner shell or its contents.

This object is carried out successfully by the construction hereinafter described, and 25 shown in the drawings wherein:

Figure 1 is a horizontal section through the refrigerator.

Figure 2 is a vertical longitudinal sectional view on the line 2—2 of Figure 1.

30 Figure 3 is a vertical transverse sectional view on the line 3—3 of Figure 1.

This refrigerator is an ordinary ice box whereof B designates the back or rear wall, E the end walls, D the doors, and S the space 35 for containing food and ice. It is desirable that the exterior of the walls of the usual refrigerator be of wood or like material, or at least that wood shall appear on the exterior. Accordingly the numerals 10 and 11 40 designate the rear and end panels of wood, and 12 are L-shaped corner posts.

Within the door and within each wall panel is disposed a packing 21 of comminuted material such as charcoal, sawdust, or 45 the like, in the form of slabs or plates and this material is held in place against the walls 10 and 11 in any desired manner. Spaced inwardly from said plates 21 is inner metal shell 25.

50 To hold the metal shell 25 in proper spaced position within the composition walls 21, angle plates 41 are employed. Spaced inwardly of the inner shell 25 are the shells of reinforced concrete 29, the inner face of each of which may be coated

with some moisture-proof material. Spacers 30 hold the concrete shells and plates 25 apart to provide a cold air space 31, while spacers 26 hold the concrete shells in spaced relation to the metal shell 25. 60

The inner concrete shell is divided into four separate chambers I, F', F², and F³, the former containing ice, and the other three being adapted to contain food. In the lower portion of the ice chamber I there is mounted 65 a metal ice shelf 32 having perforations for the passage of the drippings of the ice. In the bottom of the chamber I is located a drip pan 33, which receives the drippings which pass through the ice shelf 32. In one side 70 of the ice chamber I, at a point between the pan 33 and the shelf 32, there is formed a cold air outlet 34. It will be noted that there is a cold air space 35 extending vertically between the ice chamber I and food 75 chamber F³, on the one side, and the two food chambers F' and F², on the other side. Between the bottom of the chamber F' and the top of the chamber F², is a horizontal cold air passage 36, and a similar passage 80 37 between the bottom of the water pan 33 and the top of the food chamber F³ therebelow. These horizontal air passages communicate with the vertical spaces 31 outside of the said chambers. The inner end of 85 the passage 36 is disposed opposite the said opening 34, so that the cold air which passes out of said opening will be divided, a part of the same passing upwardly between the chambers I and F', and the other downwardly between the chambers F² and F³, and thence around the bottoms of the latter 90 chambers and upwardly and outwardly of the other chambers where it reenters the ice chamber I through an opening 39 in the top 95 thereof. A pipe 40 leads from the drip pan to the exterior of the refrigerator, where it is provided with a faucet for draining the water from the pan, or for drinking purposes. Normally the water remains in the 100 pan and helps to cool the contents of the refrigerator.

Suitable spacers 41, disposed between the different chambers, hold the chambers in proper spaced relation so that the air passages are clear for the passage of the cold air from the ice chamber. 105

What is claimed is:

A refrigerator including an outer wooden shell, a composition shell secured to the 110

wooden shell and arranged therewithin, a metal shell held in spaced relation to and within the composition shell, composition compartments spaced within the metal shell 5 and from each other to provide cold air passages therearound and therebetween, one of the compartments providing an ice chamber communicating with the said cold air passages, the lower portion of the ice chamber 10 being formed to provide a drip pan and communicating with said passages, spacers between the shells, the ice chamber having an air receiving opening in its upper wall.

In testimony whereof, I affix my signature in the presence of two witnesses.

WILLIAM K. KNUTSON.
